LEG SUPPORT FOR A CHAIR OR SIMILAR ARTICLE

Robert E. Kjer Jakobsen, Los Angeles, Calif., assignor to Schlumberger Limited (Schlumberger N.V.), Houston,
Tex., a corporation of the Netherlands Antilles

Filed Feb. 9, 1966, Ser. No. 986

Term of patent 14 years

(Cl. D15—1)

FIG. 1 is a rear perspective view of a leg support for a chair or similar article embodying my design;

FIG. 2 is a front elevational view of the base; and

FIG. 3 is a side elevational view of the base.

I claim:

The ornamental design for a leg support for a chair or similar article, substantially as shown.
